COMBINED STAND AND TRAYS

Frank Jacoby, East Orange, N. J.

Application January 25, 1956, Serial No. 39,910

Term of patent 3½ years

(Cl. D33—12)

Fig. 1

Fig. 2

Figure 1 is a perspective view of a combined stand and trays, showing my new design.

Figure 2 is a perspective view of one of the two removable tray elements.

I claim:

The ornamental design for a combined stand and trays, as shown.
